(57) **CLAIM**

The ornamental design for a bumper hitch wobble reduction device, as shown and described.

DESCRIPTION

FIG. 1 depicts a perspective view of one embodiment of the invention.

FIG. 2 depicts a top plan view of the invention of FIG. 1.

FIG. 3 depicts a bottom plan view of the invention of FIG. 1.

FIG. 4 depicts a front elevation view of the invention of FIG. 1.

FIG. 5 depicts a rear elevation view of the invention of FIG. 1.

FIG. 6 depicts a left side elevation plan view of the invention of FIG. 1; and,

FIG. 7 depicts a right side elevation plan view of the invention of FIG. 1.
